UNITED STATES PATENT OFFICE.

WILLIAM D. LA BATT, OF CHICAGO, ILLINOIS.

PACKAGE-FASTENER.

1,347,861.

Specification of Letters Patent. Patented July 27, 1920.

Application filed February 18, 1920. Serial No. 359,657.

To all whom it may concern:

Be it known that I, WILLIAM D. LA BATT, a citizen of the United States, residing at Chicago, in the county of Cook and

5 State of Illinois, have invented certain new and useful Improvements in Package-Fasteners, of which the following is a specification.

My invention pertains to features of 10 novelty and advantage in a new and improved type of self-contained or unitary complete package-fastener, such, for example, as are suitable for use on parcel-post packages and otherwise and which may be 15 unclasped or unfastened with facility if inspection of the parcel's contents is desired. To this end the fastener or connecting appliance for detachably securing together the adjacent parts of the wrapping or confining 20 material, such as paper, pasteboard, straw-board, either plain or corrugated, and the like, comprises a pair of opposed, adhesive-coated, flexible elements, such as paper or cloth, reinforced or otherwise, connected to 25 together by a metallic, joining or uniting, fastening clamp which is so designed and constructed as to permit temporary unfastening or separation of such end stickers when desired to permit total unwrapping or 30 partial opening of the parcel and the examination of its contents. With some kinds of packages or parcels it is essential that a tag be tied thereto, and one object of the invention is to provide means in the fastener for such application of the tag.

In general, the main and salient purpose of the invention is the provision of a sticker-fastener of this general type which may be easily unfastened or unclasped when required, which firmly and securely holds the wrapping material in place, which has its ends protected or shielded and hence unlikely to become caught on other objects, which is inexpensive to manufacture, which 45 may be packed in bulk and occupy but small space, and which is so shaped and formed that a tag may be readily secured thereto.

In order that those skilled in this art may have a full and complete understanding of 50 the invention and the several advantages and benefits accruing from the use of appliances embodying the same, I have illustrated a desirable and preferred embodiment of the invention in the accompanying drawing 55 forming a part of this specification and to which reference should be had in connection

with the following detailed description and throughout the several views of which drawing like reference characters refer to the same parts.

60 In this drawing:

Figure 1 is a face view of the improved style of fastener;

Fig. 2 is a central longitudinal section on an enlarged scale; and

Fig. 3 is a back view of the appliance.

By reference to this drawing, it will be seen that the fastening device or holding-appliance comprises two, oppositely arranged, adhesive-coated, flexible or pliable 70 sticker-members 10 and 11, composed of suitable material, such as paper, cloth, or similar bodies, portions of which, if desired, may be reinforced or stiffened by pieces or sections of appropriate stuff, such 75 as pasteboard 12, 12, the adhesive-coating on the rear or reinforced faces of such members having the reference characters 13, 13. As is clearly illustrated, these two companion or co-operative elements 10 and 11 are 80 in alignment or register with one another and in the same plane, although reversely disposed, with their adjacent edges or ends 14 and 15 spaced somewhat apart for a purpose hereinafter indicated. Such adhesive 85 fastening-elements are more or less firmly held in the proper matching position or co-operative relation indicated, by a uniting, bent, sheet-metal clip or fastener 16 made from a section of flat metal ribbon or band 90 bent to appropriate shape. At the back of the fastener or securing appliance, that is, the side on which the stickers 10 and 11 have their adhesive-coatings, such thin metal body extends longitudinally and desirably centrally of the device, bridging or spanning the space between the adjoining edges 14 and 15 and bearing against the back faces of the reinforcing elements.

Both end portions 17 and 18 of such metal 100 clamp pierce the stiffened portions of the attachment elements 10 and 11, that is to say, extend forwardly through slots or apertures 19 and 20 therein, and in front of the stickers the ends or tabs 17, 18, are bent 105 down flat toward one another against the front faces of the stickers, except that their terminal portions 21 and 22 are bent or curved upwardly slightly away from such faces to facilitate detachment when desired.

110 These two front ends or metal tabs or ears are preferably of the same length as

- shown so that either one may be bent up with equal facility to unclasp or unfasten the appliance as a whole to permit opening of the package. They are also equally and 5 readily accessible since each has its end flared upwardly or outwardly, thus readily permitting the introduction of any suitable implement, such as a knife-blade, under the tab to assist in its bending. The turning up 10 of either one of such metal ends or tabs permits its removal or detachment from the corresponding sticker, and, accordingly, no attention need be paid as to which of the two ends is manipulated to permit such separation of the parts.

Between the spaced edges 14 and 15 of the attachment-elements, the metal strip or clamp is looped upwardly or outwardly at 23 to provide an eye for the securing of the 20 cord or wire of a tag thereto, such portion of the clip also affording a shield or protection to the adjacent upturned ends 21 and 22 of the clip, hence eliminating any 25 possibility of their catching on or tearing other bodies with which they otherwise might come in contact. It will be seen, therefore, that the sticker members are positively held separated to provide a suitable space between them for the accommodation 30 of the loop or eye for the attachment of a tag, such portion of the clip acting also as a guard or shield for its upwardly-curved ends.

From an understanding of this invention 35 it will be seen that the fasteners can be bunched and shipped in superposed relation or stacked on top of one another, thus occupying a minimum of space. The paper sticker-elements are so firmly held between 40 the parts of the metallic clamp that they remain in proper register at all times without danger of mal-alinement or twisting out of position.

Although in this application only one embodiment of the invention has been illustrated and described, it is to be understood that the invention is susceptible of a variety of embodiments and is not limited or restricted to the precise and exact structural details presented, since these may be 50 changed in more or less radical ways without departure from the substance and essence of the invention and without the sacrifice of any of its substantial benefits and 55 advantages.

I claim:

1. A self-contained separable package-fastener of the character described including in combination a pair of sticker-elements adhesive-coated on their back faces for application to the package, and a metal clip detachably securing said elements together and having a flexible end portion overlying the front face of one of said elements and adapted to be bent up to permit

disconnection of said elements and normally shielded by a part of the clip, substantially as described.

2. A self-contained separable package-fastener of the character described including in combination a pair of sticker-elements adhesive-coated on their back faces for application to the package, and a clip detachably securing said elements together and having flexible opposed end portions 75 either one of which may be bent up to separate the fastener, said end portions being normally shielded by a part of the clip between them, substantially as described.

3. A self-contained separable package-fastener of the character described including in combination a pair of sticker-elements adhesive-coated on their back faces for application to the package, and a metal clip detachably securing said elements together and having flexible opposed end portions lying flat against the front faces of such elements either one of which may be bent up to separate the fastener, said end portions having outwardly-bent terminal 80 parts normally shielded by a part of the clip between them, substantially as described.

4. A self-contained separable package-fastener of the character described including in combination a pair of spaced sticker-elements adhesive-coated on their back faces for application to the package, and a clip detachably securing said elements together and having a flexible end portion adapted 95 to be bent up to separate the fastener normally shielded by a part of the clip in the space between said elements, substantially as described.

5. A self-contained separable package-fastener of the character described including in combination a pair of spaced sticker-elements adhesive-coated on their back faces for application to the package, and a metal clip detachably securing said elements together and having flexible opposed end portions overlying the front faces of said elements, either one of which end portions may be bent up to permit disconnection of said elements, said end portions being normally shielded by a part of the clip in the space 110 between said elements, substantially as described.

6. A self-contained separable package-fastener of the character described including in combination a pair of spaced sticker-elements adhesive-coated on their back faces for application to the package, and a metal clip detachably securing said elements together and having flexible opposed end portions lying flat against the front faces of such elements either one of which may be bent up to separate the fastener, said end portions having outwardly-bent terminal 125 parts normally shielded by a portion of the 130

clip in the space between said elements, substantially as described.

7. A self-contained separable package-fastener of the character described including in combination a pair of sticker-elements adhesive-coated on their back faces for application to the package, and a clip detachably securing said elements together and shaped to provide means for the attachment of a tag thereto, substantially as described.

8. A self-contained separable package-fastener of the character described including in combination a pair of spaced sticker-elements adhesive-coated on their back faces for application to the package, and a metal clip detachably securing said elements together and having a portion in the space be-

tween said elements formed for the application of a tag thereto, substantially as described.

9. A self-contained separable package-fastener of the character described including in combination a pair of spaced sticker-elements adhesive-coated on their back faces for application to the package, and a metal clip detachably securing said elements together and having opposed end portions either one of which may be bent up to separate the fastener, said end portions being normally shielded by a part of the clip in the space between said elements shaped for the application of a tag thereto, substantially as described.

WILLIAM D. LA BATT.
